UNITED STATES PATENT OFFICE

2,503,728

SIGNALING SYSTEM FOR SINGLE-TRACK
RAILROADSWilbur V. Grosjean, Omaha, Nebr., assignor to
The Union Switch and Signal Company, Swiss-
vale, Pa., a corporation of Pennsylvania

Application November 23, 1946, Serial No. 711,851

11 Claims. (Cl. 246—33)

1

My invention relates to signaling systems for single track railroads, and more particularly to improvements in such systems to provide increased stopping distances required for the protection of high speed trains while avoiding unnecessary restrictions upon the movement of trains which are approaching a meeting point such as a passing siding, from opposite directions.

The principal object of my invention is the provision of means by which the engineman of a train approaching a possible meeting point such as a passing siding, by performing some act of acknowledgment to indicate whether or not it is his intention to stop, such as by blowing a whistle or the like, may control the aspects of the signals for the block in advance of his train, for both directions. More particularly, my invention provides means by which the engineman is enabled to cause the entering signal for the single track block beyond the siding which he is approaching to indicate stop or proceed, depending upon whether or not the siding is a designated meeting point, and thereby avoid the display of a succession of restrictive signals to an opposing train, permitting it to approach a meeting point at a relatively higher speed than would be the case, for example, if the block signals were arranged to stand normally at clear and were not subject to control by approaching trains.

My invention is of particular advantage in the control of traffic which includes trains operated at relatively high speeds, in which case the control limits for the signals may be greatly extended in order to provide the stopping distances necessary for the protection of approaching trains if they should happen to pass signals at proceed at exactly the same time.

I shall now describe one form of apparatus embodying my invention and shall then point out the novel features thereof in claims.

In the accompanying drawings, Figs. 1A and 1B taken together illustrate the circuits and apparatus for a typical block system of the absolute permissive type, modified in accordance with my invention and arranged for the control of train movements over a stretch of single track railway which, as shown by the track plan, is equipped with automatic block signals 2 to 15, inclusive.

The main track, as shown, is divided into sections 2T to 15T, inclusive, each section being equipped with the usual normally closed track circuit having a track relay TR at one end energized by a battery TB connected across the rails at the opposite end. The signals as shown are

of the color light type, governed by polarized relays HD of the retained neutral type controlled over cascade-connected line circuits which include front contacts of the track relays. The polarity of the current supplied to each relay HD is governed in accordance with the position of the similar relay for the next signal in advance, or by a pole changer relay PC controlled thereby, and at intermediate locations, by directional stick relays SR such as are generally provided in systems of this character.

A local source of current is provided at each signal location for energizing the various circuits, but to simplify the circuits, only the terminals of the sources are shown, these being identified by the reference characters B and C, which designate the positive or supply terminal and the negative or common return terminal, respectively, in each case. Each signal is provided with three lamps, as shown in detail for signal 3, including a lamp R which is lighted to indicate stop, when the controlling relay HD is deenergized, and two lamps Y or G which are lighted to indicate caution or proceed when the signal relay HD is energized in its reverse or normal direction, respectively.

To illustrate my invention I have chosen a stretch of track including a single track block which is relatively short in comparison with the stopping distances which it is necessary to provide for the protection of opposing trains, this block having the opposing entering signals 7 and 10 and a single pair of intermediate signals 8 and 9. The stopping distance for a high speed train is assumed to be nearly equal to the distance from signal 7 to signal 9 or from signal 10 to signal 8, and to exceed the distance from signal 5 to signal 7 or from signal 12 to signal 10. It follows that if the signals were arranged to stand normally at clear, in accordance with the usual practice in automatic block signaling of this type, it would be necessary to extend the control limits for signals 5 and 7 to the location of signal 12, and those for signals 12 and 10 to the location of signal 5. This is because of the chance that opposing trains might pass signals 5 and 12 at clear at the same time, putting signals 9 and 8 to stop, in which case signals 7 and 10 would display caution indications to the approaching trains and the block sections between these two signals would provide the required stopping distances.

Assuming that the signals stand normally at clear and that the double track section between signals 11 and 12 is a designated meeting point

for the approaching trains, the westbound train will pass signal 12 at reduced speed, stopping in section 11T, which is within the extended control limit for signal 5 which it would be necessary to provide if signals 7 and 10 were arranged to stand normally at clear. If at this time the eastbound train is in section 4T, for example, signal 10, in front of the standing westbound train would display an unnecessary proceed indication while signals 5, 7 and 9 in front of the eastbound train would each indicate caution, requiring this train to reduce speed upon passing signal 5 and to continue at reduced speed past signals 7 and 9, even though adequate stopping distance would be provided if the train were to proceed at full speed after passing signal 5 and would begin to reduce speed upon passing signal 9 at caution.

One object of my invention is the provision of means for avoiding the display of unnecessary caution signals such as signals 5 and 7 in the example described, to a train which is approaching a designated meeting point and thereby overcoming an avoidable delay in train operation.

As shown herein, the circuits for the entering signals 7 and 10 are normally open so that these signals stand normally at stop. Signals 7 and 10 may be cleared, only one at a time, by the energization of an approach relay 7AR or 10AR by means controllable by the engineman of a train approaching the corresponding distant signal 3 or 14, or by the operation of a push button 7PB or 10PB at the entering signal location. Signals 7 and 10 are interlocked by time locking relays 7ASR and 10ASR governed by thermal relays 7TE and 10TE, which serve to prevent the clearing of either entering signal for a predetermined time interval following the return of the other entering signal to its stop position. The push buttons PB also provide means enabling the established traffic direction to be reversed, with the permission of the dispatcher, and the relays ASR provide the usual time locking protection effective if signal 7 or 10 is manually put to stop in front of an approaching train.

Signal 5 stands normally at caution as shown, and signal 3 as well, in order to provide adequate stopping distance for a train approaching signal 7 at stop. Similarly, the two successive signals in the rear of each of the entering signals 4, 10 and 13 stand normally at caution, as shown.

The approach relays 7AR and 10AR are controlled by sound responsive devices such as a microphone 16 located adjacent a wayside marker M a sufficient distance in the rear of signal 3 or 14, respectively, to enable that signal to assume its proceed aspect before it is passed by an approaching train in response to the actuation of the microphone by a whistle on the train, sounded at the marker location.

Suitable approach control apparatus of this kind is well known, as shown for example, by Letters Patent of the United States, No. 1,858,897, granted to Samuel M. Lucas, on September 12, 1928, for Railway switch controlling apparatus, and No. 2,138,878, granted to Robert M. Phinney, on December 6, 1938, for Railway traffic controlling system. This apparatus may be variously arranged as pointed out in these patents, and as herein shown, the microphone 16 in section 2T is energized by current from a local battery 17 in response to the energization of the directional stick relay 3SR when an eastbound train enters section 2T, and is deenergized by the release of relay 3HD when the train enters section 3T, and

when activated by a whistle signal supplies a tone frequency through suitable amplifying and filter circuits to a rectifier 18 connected to relay 7AR, this apparatus being so arranged that relay

5 7AR picks up in response to a whistle signal of suitable character to complete a stick circuit at the lower back contact of relay 7HD and to close a contact in the circuit for relay 7HD.

Signal 3 indicates caution for the reason that 10 the signal relay 3HD is energized in the reverse direction over a circuit extending over front contacts of the track relays 3TR and 4TR, and back contacts of relays 2SR and 4HD associated with the opposing signals, to terminals B and C 15 at the pole changer contacts of relay 5PC, which relay is energized only when signal 5 indicates proceed. Signal 5 indicates caution because relay 5HD is energized in the reverse direction over a circuit extending over front contacts of the track 20 relays 5TR, 6TR and 7TR and the pole changer contacts of relay 7HD to terminals B and C at the location of signal 7.

In response to the energization of relay 7AR, relay 7HD becomes energized in the normal direction

25 over the circuit including front contacts of relays 7AR, 7TR, 8TR, wires 19 and 20, front contacts of relay 9HD, a back contact of relay 8SR, normally closed contacts of push button 10PB and of relay 10TE, to terminals B and C 30 at the front contacts of relay 10ASR, causing signal 7 to indicate proceed, and releasing relays 7AR and 7ASR.

Relay 7ASR opens the circuit for relay 10HD, thereby holding signal 10 at stop even though 35 relay 10AR is inadvertently operated by the blowing of the whistle of a westbound train in section 15T.

Relay 9HD is energized in the reverse direction so that signal 9 indicates caution, over a circuit 40 similar to that for relay 3HD, already traced.

It will be seen therefore that when relay 7AR is actuated by blowing the whistle of an eastbound train in section 2T, with the apparatus in the condition shown, relay 7HD becomes energized in the normal direction to cause signal 7 to indicate proceed. Consequently relay 5HD assumes its normal position causing signal 5 to indicate proceed. Relay 5HD energizes relay 5PC which operates relay 3HD to its normal position 50 causing signal 3 to indicate proceed.

If now the section between signals 11 and 12 is a designated meeting point for opposing trains, the engineer of the westbound train will refrain from blowing the whistle at the marker location

55 in section 15T, and will pass signal 12 at reduced speed and stop before passing signal 10, which signal will continue to indicate stop. If his train occupies the main track, signal 11 will be held at stop and signal 9 at caution. The engineman of 60 the eastbound train, by blowing his whistle at the marker location in section 2T causes signals 3, 5 and 7 to indicate proceed, and his train is thereby enabled to advance at full speed to signal 9, prepared to stop in the section between signals 9 and 65 11, which as already explained, provides adequate stopping distance.

This results in a considerable saving in time for both trains, as will be readily apparent in view of the fact that the sections between signals 3 70 and 7 and between signals 7 and 9 which the eastbound train would otherwise have to traverse at reduced speed are each of sufficient length to provide stopping distance for a high speed train.

It is to be understood that similar arrangements, not shown, may be provided for the ad-

joining blocks having the entering signals 13 and 4, respectively.

It follows, therefore, that in the case just described, if the westbound train has entered the siding between signals 11 and 12 or if that siding is not a designated meeting point, and if, in addition the block governed by signal 13 is unoccupied, the engineman of the eastbound train may cause signals 9, 11 and 13 to indicate proceed by blowing his whistle in section 8T to operate an approach relay AR, not shown, to energize relay 13HD.

It will be seen that relay 7HD is arranged as a stick relay, and is released by relay 7TR when the eastbound train passes signal 7, and when the train enters the track section 8T, relay 9SR is picked up by the release of the track relay 8TR. Relay 9HD is released when the train enters section 9T, and holds relay 9SR energized until the train vacates section 10T. When relay 9SR is energized, relay 7HD may be energized in the reverse direction by the operation of relay 1AR by the engineman of a following train, to cause signal 7 to indicate caution and signals 5 and 3 to indicate proceed. If relay 1AR is operated when the first train is in the section 7T or 8T, relay 7HD will remain released, and relay 7AR will be held picked up over its stick circuit so that relay 7HD will pick up when that section is vacated. If the first train is in section 3T or 4T, or in section 5T or 6T, the circuits controlled by microphone 16 are opened by the release of relay 3HD or 5HD, and relay 7AR is not controllable by a following train, as will be obvious.

Signal 7 may also be cleared by the operation of the push button 7PB, in the event the microphone in section 2T has not been actuated, as would be the case if the passing tracks between signals 5 and 6 were a designated meeting point and the eastbound train occupied the side track. The push button 7PB has a normally open contact in the circuit for relay 7AR, and a normally closed contact in the circuit for relay 10HD, which circuit is similar to that for relay 7HD.

Assuming that the double track section between signals 11 and 12 is the designated meeting point and that signal 10 has been inadvertently cleared by the operation of the approach relay 10AR, by the engineman of the westbound train, although this train stops in the section between signals 11 and 12. In this case signal 7 will be held at stop, due to the fact that signal 10 has been cleared, and to advance the eastbound train to meet the westbound train in that section, the crew of the eastbound train will operate the push button 7PB, thereby energizing relay 7AR and releasing relay 10HD, to return signal 10 to stop, whereupon the thermal relay 10TE becomes energized, and after a suitable time interval energizes relay 10ASR. Relay 10TE is thereby deenergized and returns to its normal position after a further time interval, completing the circuit for relay 7HD, which then picks up to release relay 7AR and to cause signal 7 to indicate proceed.

If through inadvertence, button 7PB is operated when a westbound train is approaching signal 10 but is unable to stop without overrunning that signal, its presence in section 10T will prevent the clearing of signal 7, as will be clear from the circuits.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination with a stretch of railway track including a single track section having normally deenergized entering signals at its opposite ends controllable in accordance with traffic conditions for governing the movement of traffic into said section, a distant signal located in the rear of each entering signal and controlled thereby so as to indicate proceed only when such entering signal is energized, for governing traffic approaching said single track section, an approach relay at each end of the stretch, approach control means manually controllable by blowing a whistle or the like on a train approaching either distant signal for selectively actuating the approach relay at the corresponding end of said single track section, and means governed by each approach relay when actuated for causing one entering signal to be energized in accordance with traffic conditions in said stretch and for preventing the energization of the other entering signal, to thereby establish a particular direction for traffic movements in said section depending upon which approach relay is actuated.
2. In combination with a stretch of railway track including passing sidings at its opposite ends connected by a section of single track, an entering signal at each end of said single track section for governing the movement of traffic into such section, a distant signal at each end of the stretch governed by traffic conditions therein, and reflecting the condition of the associated entering signal, for governing the movement of traffic approaching such entering signal, an approach relay at each entering signal location, means controlled by each approach relay when actuated for causing one entering signal to be cleared in accordance with traffic conditions in the single track section and for preventing the energization of the other entering signal, to thereby select a particular direction for traffic movement into said section, means manually controllable by blowing a whistle or the like on a train approaching either distant signal, when such signal is energized, for selectively actuating the approach relay at that end of the single track section.
3. In combination with a stretch of railway track including a single track section through which traffic may move in either direction, a block signaling system including entering signals for both directions controllable in accordance with traffic conditions in said single track section, a distant signal located in the rear of each entering signal, and governed thereby for controlling the movement of traffic toward such entering signal in accordance with traffic conditions in the intervening portion of said stretch, an approach relay for each direction, located at opposite ends of said single track section, control means located in the trackway in the rear of each distant signal and responsive to sound waves from a train whistle or the like, means controlled by each such control means, if operated when the track portion between the adjacent distant signal and the corresponding end of the single track section is unoccupied, for selectively operating the approach relay at the corresponding end of the single track section, and means controlled by each approach relay when operated by its control means for closing a circuit controlling one entering signal and for opening a circuit controlling the other entering signal to select a particu-

lar direction for traffic movement in said single track section.

4. In combination with a stretch of railway track including an approach section at each end and an intervening single track section through which traffic may move in either direction, an entering signal at each end of said single track section, a signal relay for each signal having an energizing circuit controllable in accordance with traffic conditions in said single track section, an approach relay for each entering signal, control means located in the trackway in approach to each entering signal effective when actuated to pick up the approach relay for such signal, a stick circuit for each approach relay which is opened when the signal relay for the associated entering signal is energized, means controlled by each approach relay when energized for closing the energizing circuit controlling one entering signal and for opening a circuit controlling the other entering signal to select a direction for traffic movements in said single track section which depends upon which signal relay is energized, and manually operable means on a train effective only when such train is approaching but has not entered said stretch for selectively actuating the control means for the approach relay for the entering signal which such train is approaching to pick up such approach relay.

5. In combination with a stretch of railway track including an approach section at each end and an intervening single track section through which traffic may move in either direction, an entering signal at each end of said single track section, a signal relay for each signal for governing the indications displayed by such signal, an energizing circuit for each signal relay controllable in accordance with traffic conditions in said single track section, an approach relay for each entering signal having pick-up and stick circuits, control means located in the trackway in approach to each entering signal effective when actuated to pick up the approach relay for such signal to complete its stick circuit, means controlled by each approach relay when energized for controlling the energizing circuits for said signal relays to govern the indications displayed by both signals to designate a direction for traffic movements in said single track section which depends upon which approach relay is energized, manually operable means on a train effective only when said train is approaching but has not entered said stretch for selectively actuating the control means for the approach relay for the signal which said train is approaching to pick up such approach relay, and means for releasing the energized approach relay controlled by the associated signal relay and rendered effective when such signal relay becomes energized.

6. In combination with a stretch of railway track including an approach section at each end and an intervening single track section through which traffic may move in either direction, an entering signal at each end of said single track section, train carried acknowledging means by which the engineman of an approaching train may indicate whether or not it is his intention to stop in the adjacent approach section without entering said single track section, a signal relay for each signal for governing the indications displayed thereby, an energizing circuit for each signal relay controllable in accordance with traffic conditions in said single track section, an approach relay at each end of said single track section, control means in the trackway at locations

adjoining the ends of the stretch for actuating the approach relay at the corresponding end of the single track section in response to the operation of the acknowledging means on an approaching train, and means controlled by each approach relay when actuated for so controlling the energizing circuits for said signal relays that one entering signal is held at stop while the other is caused to display a less restrictive indication for the control of traffic movements into said single track section in a direction dependent upon which approach relay is energized.

7. In combination with a stretch of railway track including an approach section at each end and an intervening single track section through which traffic may move in either direction, an entering signal at each end of said single track section and a distant signal in the rear thereof for governing traffic movements into the adjacent approach section, train carried acknowledging means by which the engineman of an approaching train may indicate whether or not it is his intention to stop in the adjacent approach section without entering said single track section, a signal relay for each signal for governing the indications displayed thereby, an energizing circuit for each signal relay controllable in accordance with traffic conditions in said stretch in advance of the signal which such relay controls; an approach relay at each end of said single track section, control means in the trackway in the rear of each distant signal for energizing the approach relay at the corresponding end of the single track section in response to the operation of the acknowledging means on a train approaching such distant signal, and means controlled by each approach relay when energized for so controlling the energizing circuits for said signal relays that one entering signal is held at stop to hold a train at a designated meeting point which includes the approach section at one end of the stretch and the other entering signal and its distant signal are caused to display less restrictive indications to advance a train governed thereby with less delay to said meeting point.

8. In combination with a stretch of railway track including an approach section at each end and an intervening single track section having an entering block signal at each end, approach control means at the opposite ends of said single track section, circuits for clearing said block signals to establish opposite directions for traffic movements through said single track section in accordance with traffic conditions therein, train carried acknowledging means including a call signal transmitter operable by the engineman of a train approaching said stretch, a wayside receiver for each end of the stretch responsive to the operation of the transmitter on a passing train for actuating the approach control means at the corresponding end of said single track section, means governed by each approach control means when actuated for holding the block signals for one direction only at stop to thereby establish the opposite direction for traffic movements through said single track section and means associated with said signals for maintaining such direction established only until a train passing through said stretch in said opposite direction vacates said single track section.

9. In combination with a stretch of railway track including an approach section at each end and an intervening single track section having an entering block signal at each end, circuits for controlling said block signals in accordance with

traffic conditions in said single track section, approach control means at each end of said section for governing said signal circuits, each effective when actuated to prevent the clearing of the block signal at one end only, and thereby establish opposite directions for traffic movements through said single track section, train carried acknowledging means including a call signal transmitter, and a wayside receiver responsive to the operation of said transmitter by the engineman of a train when approaching said stretch for actuating the approach control means at the adjacent end to establish a particular direction for traffic movement through said single track section, and means rendered effective when a train enters said single track section for maintaining such directional control only until the single track section is vacated.

10. In combination with a stretch of railway track including an approach section at each end and an intervening single track section having an entering block signal at each end, circuits for controlling said block signals in accordance with traffic conditions in said section, approach control means at each end of said section, each effective when actuated to open a circuit controlling one entering block signal and to close a circuit for clearing the other entering block signal, train carried acknowledging means including a call signal transmitter operable by the engineman of a train when approaching said stretch, and a wayside receiver responsive to the operation of the transmitter on a passing train for actuating the approach control means.

11. In combination with a stretch of railway track including an approach section at each end and an intervening single track section having entering block signals at its opposite ends, signal

circuits for controlling said block signals in accordance with traffic conditions in said single track section, a distant signal located in the rear of each entering block signal for governing traffic approaching said single track section, approach control means at the opposite ends of said single track section each effective when actuated to control said signal circuits, one approach control means being effective to establish one direction and the other the opposite direction for traffic movements through said single track section, train carried acknowledging means including a call signal transmitter operable by the engineman of a train approaching said stretch, a wayside receiver in the rear of each distant signal responsive to the operation of the transmitter on a passing train for actuating the approach control means at the corresponding end of said single track section, to thereby clear the entering block signal for such train, and means controlled by such entering block signal for clearing the distant signal which such train is approaching to permit the unretarded movement of such train in response to the actuation of said approach control means.
